UNITED STATES PATENT OFFICE.

KATHRINE G. BARRON, OF FARIBAULT, MINNESOTA.

MAIL-CART.

1,130,464.

Specification of Letters Patent. Patented Mar. 2, 1915.

Application filed May 26, 1914. Serial No. 841,125.

To all whom it may concern:

Be it known that I, KATHRINE G. BARRON, citizen of the United States, residing at Faribault, in the county of Rice and State of Minnesota, have invented certain new and useful Improvements in Mail-Carts, of which the following is a specification.

This invention relates to mail carts and has as its object to provide a cart adapted especially to be employed by letter carriers in the delivery of mail matter.

The object of the invention is to overcome the disadvantages arising from the use of mail sacks, such for example, as the loss of mail from the sacks while being carried and the inconvenience experienced in carrying the heavily filled sacks as is now necessary. Another disadvantage arising from the use of the ordinary mail sack lies in the fact that it is frequently necessary for the carrier to remove one or more bundles of mail matter from the sack in order to secure the next bundle to be distributed. It is customary for the carrier to arrange the mail matter to be distributed along certain groups of streets or over certain areas in separate bundles and these bundles are placed in the mail sack usually in a promiscuous manner and without any identification means whatsoever to indicate to the carrier the streets or areas over which the different packages are to be delivered. It is therefore one aim of the present invention to provide a mail cart so constructed that it may be conveniently pushed about from place to place and so arranged that the several bundles of the mail matter may be placed in separate compartments, each compartment being arranged to contain the mail matter to be distributed over a certain area, so that if the compartments are systematically used, the carrier can always readily determine in just what compartment the package is contained which is next to be distributed.

Another aim of the invention is to so mount the cart that it may be readily turned about in a small space and will, in itself, be compact and convenient to move about.

A feature of the invention resides in a novel construction of supporting frame for the body of the cart.

In the accompanying drawings: Figure 1 is a perspective view of the cart embodying

the present invention. Fig. 2 is a vertical longitudinal sectional view therethrough. 55 Fig. 3 is a bottom plan view. Fig. 4 is a vertical transverse section on the line 4—4 of Fig. 2.

Corresponding and like parts are referred to in the following description and indicated 60 in all the views of the accompanying drawings by the same reference characters.

In the drawings the cart is illustrated as mounted upon a wheeled supporting frame and this frame includes a horizontally disposed substantially U-shaped body, the sides of which are indicated by the numeral 1 and the arched rear end by the numeral 2, the sides being preferably parallel as clearly shown in Fig. 3 of the drawings. A squared 65 axle 3 is secured to the under side of the side members 1 and projects at its ends beyond the side members and has mounted upon its said ends supporting wheels 4 which are of such diameter as to support the frame the 70 desired distance above the ground surface. A bearing bracket substantially V-shaped in form and including arms 5 is disposed 75 against the under side of the frame at the rear end thereof and has the forward ends 80 of its arms secured, as at 6, to the sides 1 approximately at the juncture of these sides with the connecting portion 2. The bracket is provided with a relatively wide flange 7 at the juncture of the rear ends of its arms 85 5 and this flange rests against the under side of the connecting portion 2 in the manner shown in Figs. 2 and 3 of the drawings. The flange 7 is provided with an integral bearing sleeve 8 rearwardly displaced with respect 90 thereto and extending below the plane thereof, the bearing sleeve being braced by means of an integral web 9. A yoke bearing 10 is provided at its upper end with a stem 11 fitting rotatably within the sleeve bearing 8 95 and held in place by means of a nut 12 threaded upon its upper end and bearing upon the upper end of the sleeve. A caster wheel 13 has its spindle 14 journaled in the lower end of the yoke bearing and it will be 100 apparent that this caster wheel supports the connecting portion 2 or, in other words, the rear end of the supporting frame for the body. In order that the caster wheel may be of relatively small diameter so that the cart 105 may be more readily turned in a small space

and in order to support the body of the cart at the desired elevation, supporting blocks 15 are secured upon each of the side members 1 of the supporting frame in front to rear alinement and are located one above the axle 3 and the other rearwardly of the said axle.

The body of the cart is of hollow rectangular construction and for the most part is 10 preferably formed from sheet metal. The sides of the body are indicated by the numeral 16, the top being indicated by the numeral 17 and the bottom by the numeral 18. The bottom is preferably, although not 15 necessarily, of wood and is secured in any suitable manner between the lower edges of the sides 16. The top 17 is formed in two parts spaced from the transverse middle of the top of the body and these parts of 20 course extend transversely between the upper edges of the sides 16. The rear section of the top is provided with a depending transversely extending flange 19 and the forward section of the top is provided at its 25 forward edge with a horizontal flange 20, these flanges being preferably reinforced by transversely extending cleats 21.

It is contemplated that a compartment shall 30 be provided at the middle of the cart for the purpose of receiving packages and other mail matter too bulky to be disposed within the other smaller compartments, which will be presently described, and to this end the cart body is divided transversely by partitions 22 which are vertically disposed and 35 which extend beneath the rear and forward edges respectively of the front and rear sections of the top, these partitions of course extending from the edges of the said sections to the bottom 18 of the body. This 40 compartment is indicated in general by the numeral 23.

In order that the package receiving compartment 23 may be closed and the packages 45 contained therein protected from the elements, the compartment is provided with a closure comprising two sections, one indicated by the numeral 24 and the other by the numeral 25, these sections being hinged 50 respectively at their rear and forward edges, as at 26, to the edges of the sections 17 and being provided at their sides with depending flanges 27 which lie immediately inwardly of the sides of the body when the 55 top sections are in closed position. The lateral edges of the closure sections 24 and 25 project a short distance beyond the flanges 27 and when the sections are in closed position, these projecting lateral 60 edges rest upon the upper edges of the sides 16. The free edge of one of the sections, for example, the one indicated by the numeral 25, is arranged to overlap the corresponding edge of the other section so as to 65 exclude rain, and the said section 25 is pro-

vided with a knob or other suitable handle 28, whereby it may be swung open. It will be apparent that when the sections comprising the closure are in open position, they will rest upon the top sections 17 and consequently be out of the way and free access may be had to the compartment 23 for the introduction and removal of mail matter. In front and in rear of the front and rear partitions 22, the body of the cart is provided with horizontally disposed partitions 29 and the spaces above and below these partitions are divided by vertically disposed partitions 30 arranged in the front to rear median line of the body. The partitions 22, 29 and 30, in connection with the bottom 18 and top sections 17, divide the front and rear end portions of the body into drawer receiving compartments, indicated in general by the numeral 31 within each of which there is arranged a drawer 32 preferably of sheet metal and provided with the usual sides, closed rear end, and front, the latter being indicated by the numeral 33 and projecting at its edge portions beyond the planes of the top, sides and bottom of the drawer, whereby to rest against the outer edges of the partitions 29 and 30, the flanges 19 and 20, as the case may be and the forward or rear end edges of the bottom 18. 95 It will now be apparent that not only is there provided a compartment arranged to receive packages and the larger pieces of mail matter but also a number of drawers to receive bundles of letters and the like, and it will be obvious that if these bundles, 100 after being assorted at the post office, are placed by the carrier in a systematic manner in the drawers, he will at all times know which bundle is next to be opened and the 105 pieces of mail matter comprising the same distributed. In order that the drawers may be held against accidental displacement, as for example, when the cart is being moved 110 up hill or down hill, each drawer is provided upon its front 23 with a turn latch 34, the latches upon the upper drawers being arranged to engage with the lower edges of the flanges 19 or 20, as the case may be, and the latches upon the lower drawers being arranged to engage behind strips 35 secured to the outer edges of the partitions 29. Of course, if desired, each drawer may be provided with a lock to be opened by a 115 key carried by the carrier so that the cart 120 may be left standing with safety while the carrier is distributing the mail matter.

By reference to Figs. 2 and 3 of the drawings, it will be observed that the axle 3 is located forwardly of the transverse middle 125 of the cart body and that the caster wheel 13 is located rearwardly of the transverse middle of the body so that the body is supported in such a manner that there will be no tendency for it to tilt forwardly or rear- 130

wardly and yet it may be swung about or turned in a relatively small space.

In order that the cart may be readily pushed about from place to place a pair of handles 36 are mounted upon the flange 19.

Having thus described the invention, what is claimed as new is:

1. In a cart of the class described, a wheeled supporting frame, a body mounted upon the frame and divided by transverse partitions located one forwardly and the other rearwardly of its transverse middle to provide a package receiving compartment, a plurality of drawers mounted in the ends of 15 the body, and a closure for the first-mentioned compartment comprising door sections hinged at the top of the compartment and arranged when in closed position to overlap the edges of the sides of the body, 20 the said door sections being arranged at

their free edges to overlap when in closed position.

2. In a cart of the class described, a wheeled supporting frame, a body mounted upon the frame and including a top comprising sections spaced from the transverse middle of the top of the body, partitions dividing the body transversely beneath the adjacent edges of the said top sections and forming a compartment, and a closure for 25 the compartment comprising door sections hinged to the adjacent edges of the said top sections and having their free edges overlapped.

In testimony whereof I affix my signature 35 in presence of two witnesses.
